DESIGN FOR A PLACARD OR LIKE ARTICLE

Albert N. Stephens, Chattanooga, Tenn., assignor to Electric Home and Farm Authority, Incorporated, Chattanooga, Tenn., a corporation of Delaware

Application July 19, 1935, Serial No. 57,726

Term of patent 14 years

To all whom it may concern:

Be it known that I, Albert N. Stephens, residing at Chattanooga, in the county of Hamilton and the State of Tennessee, have invented a new, original, and ornamental Design for a Placard or Like Article, of which the following is a specification, reference being made to the accompanying drawing, forming part thereof, in which the single figure of the drawing is a plan view of the placard or like article embodying my new design.

The drawing is shaded to show contrasting color.

It is understood that my design may be embodied in such articles as a placard, badge, sign or pennant without departing from the spirit of my invention.

I claim:

The ornamental design for a placard or like article substantially as shown and described.

ALBERT N. STEPHENS.
